(57) **CLAIM**

The ornamental design for a roller blind chain shroud, as shown and described.

DESCRIPTION

FIG. 1 is an upper side perspective view of the roller blind chain shroud of the present design.

FIG. 2 is a left end view thereof.

FIG. 3 is a front view thereof.

FIG. 4 is a right end view thereof.

FIG. 5 is a rear view thereof.

FIG. 6 is a top view thereof; and,

FIG. 7 is a bottom view thereof.

The break lines symbolize breaks in the length of the article in which the claimed design is embodied. The appearance of any portion of the article between the break lines forms no part of the claimed design.
